UNITED STATES PATENT OFFICE.

GEORGE E. MINGES, OF ATLANTA, CALIFORNIA.

CHAFF-SEPARATOR IN THRASHERS.

SPECIFICATION forming part of Letters Patent No. 448,357, dated March 17, 1891.

Application filed July 7, 1890. Serial No. 358,020. (No model.)

To all whom it may concern:

Be it known that I, GEORGE E. MINGES, a citizen of the United States, residing at Atlanta, in the county of San Joaquin and State 5 of California, have invented certain new and useful Improvements in Chaff-Separators in Thrashers; and I do hereby declare the following to be a full, clear, and exact description of the invention, such as will enable others skilled in the art to which it appertains to 10 make and use the same.

My invention relates to improvements in traveling thrashers; and it has for its object, among other things, to provide a construction 15 whereby the chaff and straw may be separated and secured, as will be fully understood from the following description and claims, when taken in connection with the accompanying drawing, in which the figure is a side 20 elevation of a thrasher, the side wall thereof being broken away to illustrate my improvements.

Referring by letters and figures to the said drawing, A indicates the trunk of a thrashing-machine, which may be of the ordinary 25 or any approved construction, and is suitably mounted on a frame and wheels.

B indicates the rear covered end of the trunk, which is constructed in the ordinary 30 form.

C indicates an inclined endless carrier-belt, which extends the full width of the trunk and travels around an upper roller C', which is suitably journaled in the trunk, and a lower 35 roller or drum, (not illustrated,) which is situated adjacent to the thrashing mechanism. This carrier C, which may be of any ordinary or approved construction, is designed to receive the thrashed grain, chaff, and straw 40 from the thrashing mechanism.

D indicates a slightly - inclined carrier, which is preferably of the ordinary open-rake construction and passes around drum-rollers 1 and 2, which are suitably journaled in the 45 side walls of the trunk, and this carrier-belt D, which is of a width similar to the width of the trunk, may be of any ordinary or approved construction.

The forward roller 1 of the carrier D is arranged at approximately the distance illustrated from the drum-roller C' of the carrier-belt C, whereby an intervening space is af-

firmed between the two carriers to allow the grain to fall from the chaff and straw, as will be presently described. 55

E indicates a shoe of the ordinary construction, which is provided with an inclined sieve, as illustrated in dotted lines, whereby the grain received from the carriers is conducted into a suitable channel or spout and conducted from the trunk. 60

Beneath the endless carrier D, and extending the full length and width thereof, I provide a correspondingly-inclined board 'D', which serves to conduct any grain that might 65 be discharged upon the carrier with the chaff and straw back, and discharges the same upon the shoe E, before described.

At a suitable point adjacent to the rear roller of the carrier-belt D, I arrange in the 70 trunk an approximately vertical transverse division or partition wall H, which is of the proportional height illustrated and affords a partition for a receptacle into which the straw which has been separated from the grain and 75 chaff is deposited. Attached by hinges or in any other flexible manner to the bottom edges of this partition H is a swinging partition H', which extends to the bottom of the trunk and is designed for a purpose presently to be described. The bottom of this straw-receptacle is formed by a platform a, which is of a width equal to that of the trunk and of a length to reach beneath the partition H' of the receptacle, and this platform a is attached to the trunk-frame by a transverse 80 rod or lateral journals which take into bearings formed on the longitudinal side beams of the trunk at the rear end thereof, and extending from the rear end of the platform 85 a is a bar to the end of which is attached a counterbalance-weight K, and this counterbalance-weight K serves to close the platform against the bottom of the receptacle 90 when the same has been opened by a pressure 95 of the straw, as will be presently understood.

F indicates my improved chaff-box, the bottom of which forms a portion of the bottom of the trunk, as illustrated. This chaff-box F is provided with a front vertical transverse 100 wall, but its rear end is left open to allow the box to discharge its contents, as will be presently explained. Suitably attached to the bottom of the box F, at a point adjacent to

the middle thereof, is a transverse rod F'', which is journaled at its ends in suitable bearings F' on the under side of the longitudinal beams of the frame.

5 G indicates a spring-backed latch of any approved construction, which is pivotally secured to the side beam of the frame in position to normally engage the rear end of the box F and hold the same in a closed position, 10 and attached to this latch G is a string or lever which is carried to a point convenient to the operator, who, if desired, may release the chaff-box from the catch without leaving his position on the feeding-platform of the 15 thrasher.

L indicates a transversely-situated fan, which may be of any ordinary construction and may be driven in any preferable manner, and the shaft of this fan is suitably journaled 20 in the side walls of the trunk slightly forward of the shoe E, whereby any chaff that might fall with the grain upon the shoe E is blown into the chaff-box F.

In operation the grain, straw, and chaff are 25 deposited upon the carrier C from the thrashing mechanism, and are carried by said carrier to the upper end thereof, where the grain and chaff fall from the straw, and the former falls upon the shoe E while the latter is deposited in a chaff-box F, before described. The straw and the remaining chaff are carried by the carrier D to its rear end, where the straw is again subjected to the blast from the fan to separate it from the chaff, and is deposited 35 in the receptacle formed by the partitions II and II' and the end wall of the trunk. From the situation of the blast-fan it will be seen that any chaff that might fall with the grain upon the shoe is readily blown 40 into the chaff-box.

From the construction described it will be seen that when the chaff-box F is full the spring-pressed latch may be moved from engagement with the rear end thereof, when 45 the box, by reason of the greater amount of chaff being in the rear portion thereof, will tip and discharge the said chaff, when the box will resume its former position and be engaged by the spring-catch, as its front end 50 is slightly heavier than its rear discharging end.

When the box F is tipped, its forward edges will press upon the swinging partition H' and cause the same to give rearwardly against 55 the straw in the receptacle, when the platform a will give downwardly and discharge the straw, and by reason of its counterbalance-weight the said platform a will be returned to its normal position as soon as the 60 straw has been discharged.

In the practice of my invention I do not desire to limit myself to the precise construction of parts, nor to any details, as it is obvious that such changes or modifications may be made as fairly fall within the scope of my 65 invention.

Having thus described my invention, what I claim is—

1. The combination, with the trunk A, of a traveling thrasher containing the usual 70 shoe, a fan, grain and straw carriers, of the herein-described chaff-separator apparatus, consisting of the chaff-box F, secured to the bottom of the trunk A at the rear of the shoe by the spring-latch G and pivotal attachment 75 F', the floor D' beneath the straw-carrier, the covered end B of the trunk A, the division-board H, the door II', hinged to the board II, the weighted straw-platform a, and the trip-cord G', all operating substantially 80 as described.

2. The combination, substantially as described, of the trunk A, having the covered end B, suitably mounted and provided with the usual shoe, a fan, grain and straw carriers, 85 the chaff-box F at the rear of the shoe, pivotally secured at the bottom of the thrasher-trunk, the spring-latch G and the trip-cord G', the floor D', the division-board II, and the door II' in the rear of the box F, hinged to 90 the lower edge of the board II.

3. In a thrashing-machine, the combination, with an endless straw-carrier, of a blast-fan arranged at a suitable point beneath said carrier, the grain-receiving shoe provided with 95 an inclined sieve, and a chaff-box pivotally mounted upon the frame and adapted to be normally held in a closed position, substantially as described, for the purpose set forth.

4. In a thrashing-machine, substantially as 100 described, the combination, with endless carriers, as C and D, and the blast-fan arranged at a suitable point within the trunk, of the grain-receiving shoe, the pivotally-mounted chaff-receiving box adapted to be normally 105 held in a closed position, the transverse fixed wall and the swinging board forming with the end wall of the trunk a straw-receptacle, and the platform or bottom a of the straw-receptacle, pivotally connected to the rear end 110 of the trunk, and the counterbalance-weight attached to the rear end of said platform and adapted to keep the same normally in a closed position, substantially as specified.

In testimony whereof I affix my signature in 115 presence of two witnesses.

GEORGE E. MINGES.
